UNITED STATES PATENT OFFICE.

DAVID G. DEE, OF ROCHESTER, NEW YORK, ASSIGNOR, BY MESNE ASSIGNMENTS, TO
ROCHESTER H. ROGERS, OF ROCHESTER, NEW YORK.

FIRE-ALARM TELEPHONE TRANSMITTING MECHANISM.

1,225,935.

Specification of Letters Patent. Patented May 15, 1917.

Application filed February 25, 1914. Serial No. 820,948.

To all whom it may concern:

Be it known that I, DAVID G. DEE, of Rochester, in the county of Monroe and State of New York, have invented certain new and useful Improvements in Fire-Alarm Telephone Transmitting Mechanisms; and I do hereby declare the following to be a full, clear, and exact description of the same, reference being had to the accompanying drawings, forming a part of this specification, and to the reference-numerals marked thereon.

My present invention has for its object to provide certain improvements in alarm signaling mechanism and circuits controlled by it by means of which fire alarm signals may be despatched over the lines of telephone exchanges from the subscriber's station, whereby, upon the completion of the operation of the call box or sending apparatus, the subscriber's telephone circuit is restored to its normal condition in readiness to initiate a call or respond to calls despatched from the central office or exchange.

To state the object of the invention in other terms it may be said that it consists in providing the signaling mechanism with trip devices which control the alarm circuit in such a manner that it is rendered capable of despatching signals automatically after said apparatus has been started into operation and which will restore the telephone circuit to its normal condition after it has completed its last round of signals. My invention also has for its further object to provide a trouble alarm mechanism which is normally inoperative and is arranged to maintain the alarm circuit under constant test to the end that a break in the circuit, or a grounding of the conductors will automatically set up a disturbance of said trouble mechanism. This trouble circuit I also arrange so that it will be rendered inoperative when the alarm mechanism is in operation.

To these and other ends the invention consists in certain improvements and combinations of parts, all as will be herein-after more fully described, the novel features being pointed out in the claims at the end of the specification.

In the drawings:

Figure 1 is a diagrammatic view illustrating mechanism embodying my present invention, together with a simple arrange-

ment of circuits by means of which the operation of the various parts will be more easily understood, and

Fig. 2 is an enlarged detail view of the alarm mechanism.

Similar reference numerals throughout the several figures indicate the same parts.

Apparatus embodying my invention is intended to be used in conjunction with established telephone exchange systems, the fire alarm signaling or calling instruments used in conjunction therewith being adapted, when actuated, to transmit impulses of current indicating the code signal of the instrument. In illustrating the present invention the telephone subscriber's instrument circuit is shown comprising the wires A' and B' leading from the spring contacts of the central office switchboard jack J, said subscriber's circuit comprising the usual telephone set consisting of the transmitter T and receiver R. The central office apparatus is shown diagrammatically as comprising the answering and calling cord circuits, indicated by 1 and 2, respectively, supplied with current from a battery 3 and in circuit with which is the operator's set comprising the receiver 4 and the transmitter 5. Associated with the line jack J are the contacts of the customary circuit of the pilot lamp j by means of which the operator is signaled when the subscriber's circuit is closed. The fire alarm circuit leading to fire department headquarters may comprise the line wires s, s' leading from a special plug S and carrying current from the battery s² through magnets s³; the latter may, in turn, control an armature s⁴ in a local circuit supplying current from a battery s⁵ to the operating magnets of a recording device or punch s⁶.

The fire alarm box mechanism comprises an arbor C which may be driven by a spring actuated gear train of any desired construction for imparting a uniform speed of rotation thereto and adapted to rotate the arbor and the code wheel mounted thereon a plurality of revolutions for the purpose of repeating the given code signal a number of times in succession. The clock train operating the arbor C comprises a notched wheel with which an escapement pallet cooperates which is normally restrained against movement, locking the clock train,

by an arm c attached thereto which engages a restraining device such as an armature c' which may be disengaged by the operation of a release magnet c^2 which is energized when its operating circuit is closed, as will be further described.

The signal box mechanism comprises various contacts and devices for operating them which are controlled by switch operating cams and a code wheel c^4 mounted on the arbor C. The latter also carries an arm provided with a finger which extends outwardly, as indicated at c^5 coöperating with a trip lever E and a spur gear wheel F to first lift the trip and then advance the gear wheel the distance of one tooth for each complete rotation of the arbor C. The gear wheel F is journaled upon a stud f and connected thereto are two cam members F' and F^2 controlling the operation of the levers F^3 and F^4 which are journaled upon a common pivot and control the opening and closing of two different sets of contacts, by means of which the subscriber's circuit is first rendered in condition to despatch a signal, at which time the subscriber's telephone set is cut out, and which restores said circuit to its normal condition after the alarm mechanism has completed its last round. At the time the fire alarm circuit is completed and the alarm box is set into operation, a trouble alarm or trouble indicating mechanism on the subscriber's circuit is also set into action, by the release of the armature r^3 of relay R'.

Referring now to the construction of the cam wheels F' and F^2 it will be observed that they are provided respectively with the projections f' and f^2 , which in their normal position coöperate with the levers F^3 and F^4 to hold them in the position shown in Fig. 1. The projection f^2 is of a length approximately twice that of the projection f' and the former is located relatively to the latter so that as the alarm mechanism reaches the limit of its movement and stops, after the last round of signals has been despatched, said projection f^2 will contact with and operate its lever F^4 causing the contacts controlled thereby to be restored to their normal position while the contacts controlled by the lever F^3 remain in their actuated position.

The signal box mechanism further comprises a pair of spring contacts g , g' which are normally held in contact by an insulated pin f^3 on the lever F^3 and which open of their own accord when the lever is released by its cam projection f' and when open, cuts out the local trouble alarm and renders it inoperative until the box mechanism has been restored manually by the inspector. However, by reason of the length of the cam projection f^2 the telephone line is restored to its normal condition of service as

soon as the box mechanism has finished its work. There are also a set of three contacts h , h' and h^2 , the first of which is held in contact with the second by an insulated pin f^4 on the lever F^4 and through which the subscriber's telephone circuit leads under normal conditions and by means of which this circuit is interrupted. During the operation of the box the spring h moves into the dotted line position in contact with the spring h^2 and as the latter is provided with a lateral extension h^3 which coöperates with the teeth of the code wheel c^4 , said spring is moved into and out of contact with the spring h to despatch the code signal of the alarm box during the rotation of the code wheel c^4 .

The subscriber's telephone instrument circuit is illustrated as comprising the wires A and B, and the former leads directly to the contact spring h' , the circuit being continued from the spring h to the central office over the conductor A' which terminates in one of the springs of the switchboard jack. The other wire B leads to the contact spring h^2 and has attached to it the conductor B' which completes the subscriber's circuit to the central office. In the conductor B there is inserted an armature b which is normally closed against the contact b' , but which may be withdrawn therefrom by current flowing in the coils of the relay R arranged in a circuit composed of the wire r , connected to line wire B' and the wires r' , r^2 leading to the spring g . The spring g' is connected to spring h' by the tie r^{20} . The wires r' , r^2 are normally disconnected but the circuit may be completed through them by an armature r^3 and contact r^4 . This armature r^3 is normally held in retracted position by the relay R' which is included in the circuit of the release magnet c^2 .

One of the alarm box mechanisms, previously described, will suffice for a single building and a single telephone circuit, but in order that it may be set into operation from any one of a plurality of different places throughout the building, either automatically, by the use of thermostats, or manually by means of push buttons, the release magnet c^2 is employed having a local circuit of any desired length composed of the wires c^7 and c^8 supplied with current from the battery X and leading to the terminals of the windings of the coils of the relay R'. This circuit is closed and for this reason the relay R' is given a high resistance of approximately 200 ohms and the magnet c^2 is of approximately 3 ohms resistance. The thermostatic devices c^9 , or the push button c^{10} , when closed, short circuits the relay R' permitting the full strength of the current from the battery X to energize the release magnet c^2 whereupon the restraining member or armature c' is attracted

and the mechanism of the fire alarm box permitted to begin its cycle of operation. The deenergizing of the relay R' releases the armature r^3 whereupon the relay R is energized. The armature b of the last mentioned relay is connected by the tap b^2 to the wire r , and when it is attracted it engages a contact b^3 connected by the lead b^4 to the wire r' ; consequently when the armature is 5 in attracted position it short circuits the relay magnets so that it is successively pulled up and released until the circuit r , r' , r^2 is open at the contacts g , g' by the movement of the lever F³. These contacts, 10 as before mentioned, cut out the buzzer, or trouble alarm, during the operation of the signal box mechanism, but as these are closed under normal conditions the trouble indicating mechanism is always in condition to be operated in the event the actuating alarm circuit c^7 , c^8 is opened at any point.

Describing the movements of the box and the various parts thereof and the circuits by 15 which the present invention is carried out, it will be assumed in the first instance that normal conditions exist on the subscriber's instrument circuit; that is, the line wires A and B are continuous through to the central 20 office, the circuit being open at the usual receiver hook contacts of the subscriber's telephone set, the armature b of relay R resting in engagement with the contact b' . In the fire alarm box the contacts are all in the 25 normal position shown in the full lines in Fig. 1, the pairs of springs g , g' being closed together and the springs h , h' being in contact; the circuit c^7 , c^8 of the release magnet c^2 is also complete, being closed through the 30 battery X and the relay R'. The operation of the release magnet c^2 in the closed circuit, just described, is prevented by the high resistance of the relay R' which is maintained continuously in an energized condition so 35 that the operating circuit of the release magnet is always under test and any failure of the current in the circuit is indicated at once by reason of the release of the armature r^3 which, in falling back against the 40 contact r^4 completes the circuit of the trouble relay R bridging it across the telephone line. When the trouble call or indicator is set into operation through the 45 breaking of the circuit of the release magnet c^2 , it will continue to operate until the circuit is restored. When an alarm signal is 50 despatched, the trouble indicator is thrown into operation for a brief period, but is checked automatically by the alarm mechanism as soon as the contacts g , g' are separated.

I claim as my invention:

1. In a telephone fire alarm system, the combination with a subscriber's line circuit 55 having a telephone instrument set and pro-

vided with contacts normally maintaining said instrument connected to the line and which may be operated to disconnect it and close the line circuit independently of the instrument, of a trouble alarm mechanism 70 comprising a circuit having a pair of contacts and an alarm apparatus controlling the first mentioned contacts and serving to despatch current impulses over the line circuit and simultaneously operating the 75 trouble circuit contacts to break the trouble circuit.

2. In a telephone fire alarm system, the combination with a subscriber's line circuit having a telephone instrument set and provided 80 with contacts normally maintaining said instrument connected to the line and which may be operated to disconnect it and close the line circuit independently of the instrument, of a trouble alarm mechanism 85 comprising a circuit having a pair of normally closed contacts and an alarm apparatus serving to open the latter and control the line circuit contacts to despatch impulses of current over said line circuit. 90

3. In a telephone fire alarm system, the combination with a subscriber's line circuit having a telephone instrument set and provided with contacts normally maintaining 95 said instrument connected to the line and which may be operated to disconnect it and close the line circuit independently of the instrument, of a trouble alarm mechanism comprising a circuit having a pair of normally closed contacts and an alarm 100 mechanism adapted to transmit a plurality of groups of impulses controlling the line circuit contacts to disconnect the telephone set during the transmission of the impulses and subsequently reconnect it to the line 105 upon the termination of the last group of impulses, said mechanism also serving to open the trouble circuit contacts upon the commencement of the transmission of the alarm impulses and permitting them to remain open after the telephone set has been 110 reconnected to the line.

4. In a telephone fire alarm system, the combination with a subscriber's line circuit, of an alarm mechanism for despatching current impulses over said line circuit, a local circuit for setting said alarm mechanism in operation, a trouble circuit for maintaining the local circuit under constant test, and trouble circuit contacts under the control of 115 120 the alarm mechanism for opening said trouble circuit.

5. In a fire alarm telephone system, the combination with a subscriber's line circuit, of an alarm mechanism for despatching current impulses over said line circuit, a local circuit for setting said alarm mechanism in operation, a trouble circuit for maintaining 125 said local circuit under constant test and transmitting a trouble alarm over the line 130

circuit aforesaid, and trouble contacts under the control of the alarm mechanism aforesaid, for opening said trouble circuit when the alarm mechanism is actuated.

- 5 6. In a telephone fire alarm system, the combination with a subscriber's line circuit provided with a telephone set having a plurality of sets of contacts, one set constituting a pair of normally closed contacts and 10 a pair of normally open contacts through which latter the telephone line may be closed independently of the telephone set, and the remaining set constituting a pair of normally closed contacts, of an impulse despatching mechanism adapted to reverse the condition of the first set of contacts and open the second set of contacts, subsequently producing variations in the potential flow of current in the line, and finally restoring 15 20 the normally closed contacts of the first set to their normal condition, leaving the second set of contacts open.

7. In a telephone fire alarm system, a combination with a subscriber's line circuit provided with a telephone set and having two sets of contacts, the first set constituting a pair of normally closed contacts and a pair of normally open contacts through which latter the telephone line may be closed independently of the telephone set, the other set constituting a pair of normally closed contacts, a trouble alarm circuit coöperating with the second set of contacts, of an impulse despatching mechanism adapted to reverse 30 35 the condition of the first set of contacts and open the second set of contacts, and to subsequently produce variations in the potential flow of current in the line and finally restore the first set of contacts to their normal condition leaving the second set of contacts open.

8. In a telephone fire alarm system, the combination with a subscriber's line circuit, of a trouble circuit coöperating with said line circuit, a pair of normally open contacts in said line circuit, a pair of normally closed contacts in said trouble circuit, and an impulse despatching mechanism including means for coöperation with the contacts aforesaid whereby the contacts in the subscriber's circuit may be opened and closed during one operation of the alarm despatching mechanism, and those in the trouble circuit may be simultaneously opened and 50 55 maintained in such position after the com-

pletion of the operation of the impulse despatching mechanism.

9. In a telephone fire alarm system, the combination with a subscriber's line circuit including two contacts with a central contact therebetween, said central contact adapted to normally rest against one of said outer contacts, of a trouble circuit coöperating with said line circuit, a pair of normally closed contacts in said trouble circuit, and an impulse despatching mechanism coöperating with said contacts whereby the operation thereof moves the central contact of the line circuit to rest against the remaining outer contact, and simultaneously opens the contacts in the trouble circuit aforesaid.

10. In a telephone fire alarm system, the combination with a subscriber's line circuit including two contacts with a central contact therebetween, said central contact adapted to normally rest against one of said outer contacts, of a trouble circuit coöperating with said line circuit, a pair of normally closed contacts in said trouble circuit, and an impulse despatching mechanism coöperating with said contacts whereby the operation thereof moves the central contact of the line circuit to rest against the remaining outer contact, and returns said central contact to its normal position at the completion of the operation of the impulse despatching mechanism, said impulse despatching mechanism simultaneously opening the contacts in the trouble circuit at the beginning of its operation and maintaining them in such position.

11. In a telephone fire alarm system, the combination with a subscriber's line circuit, of a trouble circuit coöperating with said line circuit, a pair of normally open contacts in said line circuit, a pair of normally closed contacts in said trouble circuit, and an impulse despatching mechanism including disks for coöperation with the contacts aforesaid, the disk coöperating with the contacts of the trouble circuit being provided with a short tooth, and the disk coöperating with the contacts of the line circuit being provided with a relatively longer tooth.
